UNITED STATES PATENT OFFICE.

MELKER J. EICHHORN, OF CHICAGO, ILLINOIS.

THERMIC MOTOR.

SPECIFICATION forming part of Letters Patent No. 596,364, dated December 28, 1897.

Application filed May 17, 1895. Serial No. 549,641. (No model.)

To all whom it may concern:

Be it known that I, MELKER J. EICHHORN, a subject of the King of Sweden and Norway, residing at Chicago, in the county of Cook and State of Illinois, have invented certain new and useful Improvements in Thermic Motors, of which the following is a true and exact specification, reference being had to the accompanying drawings, forming a part hereof.

10 This invention relates to improvements in thermic motors, and has for its prime object the production of a motor of this class in which the power is produced by the agency of a gas-turbine in which the potential or latent energy of the fuel is converted into dynamic energy or physical force which can be utilized through the turbine wheel.

Another object is to store and utilize the products of the exploded gas so delivered to 20 and directed upon the turbine wheel as to practically suspend and operate the turbine wheel in space in the production of power therefrom, whereby the friction to which turbines have heretofore been subjected is reduced to a minimum.

25 A still further object is to have a thermic motor of the gas-turbine type in which the cycle of operation is contained within the machine, the operating power for the turbine being automatically produced and controlled from the turbine, the operation of the turbine rendered economical and steady in the maximum degree, and the whole machine rendered of such compactness as to occupy the minimum space.

These and such other objects as may hereinafter appear are attained by the devices illustrated in the accompanying drawings, in which—

40 Figure 1 represents a central longitudinal section of a gas-turbine embodied in my invention. Fig. 2 represents a horizontal section on the line 2 2 of Fig. 1. Fig. 3 represents a vertical section on the line 3 3 of Fig. 45 1; and Fig. 4 represents a transverse vertical section on the line 4 4 of Fig. 2, looking in the direction indicated by the arrows.

50 Similar letters and numerals of reference indicate the same parts in the several figures of the drawings.

To facilitate the understanding of the construction and arrangement of my motor, I will first describe the general operation thereof.

The motor comprises a turbine wheel, an expansion-chamber for the exploded gases, 55 an explosion-chamber, a mixing-chamber, a pump for delivering the explosive mixture under slight compression from the mixing-chamber to the explosion-chamber, and conduits or passages for conducting the explosive mixture from the mixing-chamber to the explosion-chamber and from the compression-chamber to the turbine wheel. The pump, the valves controlling the admission of air and gas to the mixing-chamber, and the 60 circuit-closing devices are operated by power taken from the turbine wheel, so that once the wheel is in motion there is a perfect cycle of operation within the motor, and the explosive mixture is admitted to the motor, 65 forced into the explosion-chamber, ignited, and exploded, then delivered to the expansion-chamber, where it is held under high compression, and from the expansion-chamber delivered to the turbine wheel for operating the same and through it producing motive power which may be utilized in any desired manner.

Referring now by letters and figures to the accompanying drawings, A indicates the turbine wheel, mounted up in a vertical shaft B, suitably journaled upon ball-bearings C in an external casing D, provided with an exhaust-port E, the products of combustion being delivered into the turbine-chamber through the 80 pipes F and G in a manner which will be described in detail further on. Suitably adjacent to the turbine-chamber is the expansion-chamber H, containing a packed piston I, 85 yieldingly forced toward one end of the said chamber by a compressible agent, such as the coiled springs J, confined between said piston and the end of the expansion-chamber. Obviously air or other compressible fluid or agent may be substituted for the coiled springs. 90

In the lower portion of the expansion-chamber is located the explosion-chamber K, connected by ducts or passages L with the expansion-chamber on the side of the piston I opposite to the spring or other compressible 95 agent. In these ducts or passages L are located suitable one-way valves—that is, valves that will open so as to permit the passage of the products of explosion from the explosion-chamber into the compression-chamber, 100 but will close to prevent the return of such

products. In the drawings I have illustrated a simple form of such a valve, comprising a pair of rollers M, suitably journaled in inclined ways N, formed in the walls of the ducts or passages L, which rollers, when actuated by superior pressure from the explosion-chamber, will back off and separate, so as to permit the products of explosion to pass by them through the ducts, but will immediately return to contact with each other and the said walls of the ways, so as to close said ducts under the combined influence of the pressure above them in the expansion-chamber and gravity.

15 In practice I propose to provide the explosion-chamber with a water-jacket through which cold water will be constantly circulated by the inlet and outlet pipes O and P for the purpose of maintaining the said chamber at 20 as low a temperature as possible. I also propose to provide the expansion-chamber with a jacket of some material which is an inferior conductor of heat, such as a magnesia jacket, so as to maintain as high a heat as practicable within said chamber and thereby enable 25 the maintenance, without material fluctuation, of as high pressure as possible in the expansion-chamber.

I may here state that while I have designated the chamber H as an "expansion-chamber" for permitting the products of explosion to expand therein against a yielding abutment this chamber may be more properly termed a "compression-chamber," for the expanded gases are maintained at all times under compression therein and are expelled therefrom largely by such compressing agent. I will therefore in future reference to this chamber, for greater clearness, refer to it as 40 a "compression-chamber."

In the explosion-chamber is located a pair of sparking-points Q, included in the secondary electric circuit of an induction-coil, which when the primary or battery circuit of said coil 45 is closed at a point external to said chamber produces a spark which causes an explosion of the gas contained in said chamber. This explosion-chamber is connected by a pipe or passage R, in which is contained a non-return 50 check-valve S with a mixing-chamber T, and between said mixing-chamber and the check-valve is located a single-acting pump U, which draws the charge of explosive mixture—i. e., air and gas—into the said chamber, where it 55 mixes and from whence it is discharged by the pump through the passage R past the check-valve S into the combustion-chamber, the inlet-valves for the mixing-chamber being so operated as to be closed during the 60 down or compressing stroke of the pump.

The pump is operated by an eccentric V upon a shaft W, through the medium of an eccentric-strap X, attached to the piston-rod Y of the pump.

65 The shaft W is driven from the turbine-shaft B by means of a beveled gear connection between the shaft W and a counter-shaft

a, which latter in turn has a gear connection b c with the turbine-shaft. Obviously this train of gears may be variously arranged without departing from the spirit of my invention so long as it serves to transmit motion from the turbine wheel with proper speed and power to perform the functions of the shaft W, which in point of fact serves the 75 purpose of a governor-shaft. Upon the governor-shaft is also mounted a cam-disk o, with which engages a spring-actuated rod p, which operates as a circuit-closer, a contact-block q on the end thereof constituting one 80 terminal of an electric battery or primary circuit and another block r, adapted and arranged for contact with the block q, constituting the other terminal of the circuit.

It will thus be readily understood that as 85 arranged in the drawings the battery-circuit will be closed, and there will be consequently one explosion for each rotation of the governor-shaft, for during each rotation the pump makes a complete stroke, draws in its charge 90 of explosive mixture, and forces the same into and slightly compresses said mixture in the explosion-chamber, and while under such slight compression the primary circuit is 95 closed, as between the terminals q and r, and the spark is produced by the induced current jumping between the spark-points Q, which are included in the secondary electric circuit.

In the drawings I have illustrated the valve controlling the admission of gas and air to the mixing-chamber as a double spring-actuated check-valve T', opening inwardly toward its chamber under the suction of the pump, the gas being delivered into the chamber T² through the pipe T³ and the air being admitted to the chamber T⁴ through the nozzle T⁵, the arrangement of these parts being best illustrated in Figs. 1 and 2.

Of course by proper variations in the train of gearing connecting the turbine-shaft with 110 the governor-shaft the number of explosions per second may be varied according to the work to be performed by the machine; but for all general purposes from six to eight explosions per second and about forty thousand 115 revolutions per minute of the turbine-shaft will prove sufficient.

The compressed products of explosion are conducted from the compression-chamber H, through the pipes or passages s and t, to the tangential and oppositely-disposed twyers F and G, which twyers, as more clearly illustrated in Fig. 3, are provided with two discharge-nozzles u and v, one above the wheel and the other below the wheel, so that the buckets of the wheel pass between each pair of discharge-nozzles. In practice I propose to give the lower nozzle on each twyer a superior capacity, so as to exert a sufficient upward force upon the turbine wheel to practically suspend and rotate the same in space, thereby relieving the bearings of the turbine-shaft from practically all duty except to maintain the same in alinement, as the fri-

tion will be practically eliminated by such an arrangement of the twyer-nozzles. To this end I propose that the ball-bearings for the turbine-shaft shall be sufficiently loose to provide play between the stationary and revolving parts, so that the turbine wheel and shaft will be left free to adjust themselves and rotate around the axis of their center of gravity without reference to the geometrical axis of the shaft and the bearings. Of course the pressure of the jets delivered from the twyer-nozzles above and below the wheel may be adjusted either separately or simultaneously with relation to each other for the purpose of properly balancing the weight of the turbine shaft and wheel, so as to not only lift the latter from its bearings, but to as nearly as possible center the same and thereby reduce the friction between the shaft and its bearings in compelling the wheel to spin practically free in space while supported upon the slightly superior force of the lower gas-jets.

In operation the series of rapid explosions, the product of which passes into the compression-chamber, serves to lift the piston of the compression-chamber against the yielding resistance of the spring or other compressible agent, which places the products of explosion under compression in said chamber, which thereby serves to store the entire potential energy of the exploded gases ready for use whenever desired. When sufficient pressure has been stored, the products of explosion are delivered from the compression-chamber direct to the turbine wheel in such volume as may be deemed advisable or desirable for the work to be performed by the motor, where the potential energy of the exploded gases may be practically entirely converted into dynamic or physical energy. The consumption of the stored or compressed exploded gases may be proportioned to practically equal the production of exploded gases by the motor, and hence a gas of practically uniform pressure may be delivered to the turbine wheel, and there will be little occasion for variations of pressure in the compression-chamber, although such variations are of course provided for in the described arrangement. In starting up, a small hand air-pump *w* may be employed for producing the initial revolutions of the turbine wheel by driving air through the nozzles upon the buckets of the wheel.

My invention is far superior in many particulars to the steam-turbine or the gas-engine as now known in the art, for there is no smoke, soot, or expense involved in producing the initial power such as is involved in producing steam, nor is there the objectionable noise of the exhaust; nor the odor or waste of energy involved in the operation of gas-engines, for practically all of the explosive force is utilized and the products of explosion are not exhausted and discharged until almost fully utilized and after their

pressure has been reduced to, or nearly to, that of the atmosphere.

In practice it will be found that a certain amount of the products of explosion will remain in the explosion-chamber after the explosion takes place, although the greater portion of the products of explosion will pass into the compression-chamber. In order to remove the surplus products of explosion, I provide a valve-chamber 10, having a normally open balanced valve 11, which is held in an opened position by means of the spring 12 between the explosions in the explosion-chamber and automatically closed during each explosion. The valve-rod 13 is connected with a bell-crank lever 14, which is pivoted on a suitable support 16 and provided with a friction-roller 17, arranged to operate in contact with a cam 19 upon the shaft *W*. This cam 19 is so constructed that the valve is closed during the time the explosion takes place, and immediately after each explosion in the explosion-chamber takes place it will be permitted to rise, so that the products of explosion which remain in chamber *K* will be permitted to escape through the valve 10 and pipe *t* into the exhaust-chamber *D*. I arrange a governor 20 on the shaft *W*, which is adapted to adjust the cam 19 on said shaft to provide for limiting the movement of the valve more or less, as desired. As the speed of the turbine and the shaft *W* increases the governor will draw the cam 19 to the right (see Fig. 1) and the valve 11 will be lifted less. Consequently a part of the exploded gases will be kept back in chamber *K* and a smaller quantity of fresh gas-and-air mixture admitted to said chamber. This will weaken the force of the consecutive explosions and tend to reduce the speed of the turbine. By these means I am enabled to adjust the force of the consecutive explosions according to the power required.

As far as I am aware, in all the motors heretofore constructed of the general class to which my invention belongs the products of explosion are admitted to the turbine wheel, either directly or indirectly, in such a way that the force of each explosion is communicated like a blow to the turbine wheel. This is exceedingly objectionable, and I have overcome such objection in my improved motor by providing a valve-chamber 21, which communicates with the pipe *s* and has a normally open valve 22, which is arranged to be automatically closed as each explosion takes place in the explosion-chamber to prevent the force of explosion from being communicated to the turbine. The valve-rod 23 of this valve 21 is pivotally connected to a bell-crank lever 24, pivoted on the support 16 and provided with a friction-roller 25, arranged to operate in contact with the cam 26, secured on the shaft *W*. As the cam 26 revolves the bell-crank lever 24 is actuated to close the valve 22 during the explosion, and which valve is caused to open immediately

after the explosion to permit the products of explosion from the expansion-chamber to pass through the pipe *s* into the twyers *F* and *G*. I am thus enabled to prevent the effect which would result if the products of explosion were permitted to pass directly to the turbine wheel and momentarily increase the speed of said wheel. The products of explosion pass through the valve *21*, which is arranged to operate in such a manner that the force of the explosion will be entirely stored in the expansion-chamber.

Having described my invention, what I claim, and desire to secure by Letters Patent, is—

1. The combination in a gas-turbine, of an expansion or compression chamber, a yielding abutment working therein, an explosion-chamber, a duct or passage connecting said chambers, and a non-return check-valve located in said duct or passage, substantially as described.

2. The combination in a gas-turbine of an expansion-chamber and explosion-chamber, a one-way-valved communication between said chambers, a pump for delivering an explosive mixture to, and compressing the same in, said explosion-chamber, a turbine wheel, nozzles communicating with the expansion-chamber

30 for directing the products of explosion to said wheel, the terminals *q*, *r* and a spring-actuated rod adapted to close the circuit and operated from the main shaft of the turbine wheel, substantially as described.

35 3. The combination in a gas-turbine, of an explosion-chamber, an expansion or compression chamber, a one-way-valved communication between said chambers, a piston in the expansion-chamber, and a spring actuating said piston and adapted to maintain the products of explosion from the explosion-chamber under pressure in the expansion-chamber, substantially as described.

45 4. The combination in a gas-turbine, of an explosion-chamber, an expansion-chamber, a one-way-valved communication between said chambers, a turbine wheel and tangentially-arranged twyers, each twyer being provided with a pair of nozzles, one located above and 50 the other below said wheel, substantially as described.

55 5. The combination in a gas-turbine, of an explosion-chamber, an expansion-chamber, a one-way-valved communication between said chambers, a turbine wheel and tangentially-arranged twyers, each of said twyers being provided with a pair of nozzles, one arranged below, the other above a turbine wheel, those below said wheel having a superior pressure, 60 substantially as described.

65 6. The combination in a gas-turbine, of a turbine wheel mounted on a vertical shaft, nozzles arranged tangentially in pairs above and below the said wheel, and means whereby the pressure of the jets delivered by said nozzles

above and below the wheel may be adjusted separately or simultaneously with relation to each other, substantially as described.

7. The combination in a gas-turbine, of a turbine wheel mounted upon a vertical shaft, 70 nozzles arranged tangentially in pairs below the periphery of the wheel, and loose ball-bearings for said shaft, substantially as described.

8. The combination in a gas-turbine, of a 75 turbine wheel mounted on a vertical shaft, nozzles arranged tangentially in pairs above and below the said wheel, and means whereby the pressure of the jets delivered by said nozzles above and below the wheel may be varied 80 with relation to each other, and loose ball-bearings for said shaft, substantially as described.

9. The combination in a gas-turbine, of an expansion-chamber, an explosion-chamber, a 85 one-way-valved communication between said chambers, a pump for delivering an explosive mixture to and compressing the same in said explosion-chamber, means for igniting said explosive mixture, a turbine wheel, and nozzles 90 communicating with the expansion-chamber for directing the exploded products of explosion to said wheel, substantially as described.

10. The combination in a gas-turbine of an 95 expansion-chamber, an explosion-chamber arranged below the expansion-chamber, a one-way-valved communication between said chambers, a pump for delivering an explosive mixture to, and compressing the same in, said 100 explosion-chamber, a vertical shaft *B*, a turbine wheel mounted upon said shaft, a cam-shaft *W* geared with said vertical shaft, a cam-disk mounted on said cam-shaft, a spring-actuated rod adapted to be operated by said 105 cam-disk, a stationary terminal block *r* and a terminal block *q* carried by the spring-actuated rod and adapted to be brought in contact with the stationary terminal block to close the circuit and cause an explosion and ignite 110 the explosive mixture in the explosion-chamber, substantially as described.

11. In a gas-turbine, the combination with an explosion-chamber, an expansion or compression chamber, a turbine and connections 115 between said turbine and the expansion-chamber, of a valve-chamber *21*, a connection between the expansion-chamber and the turbine and provided with a spring-controlled valve, a bell-crank lever pivotally secured to a 120 suitable support and connected to said valve, a cam-shaft geared to the turbine-shaft and a stationary cam arranged on said shaft and adapted to actuate said bell-crank lever to operate the valve in said valve-chamber, substantially as described.

12. In a gas-turbine, the combination with an explosion-chamber, an expansion or compression chamber, the nozzles, a turbine, a 130 turbine-shaft, a connection between said noz-

zles and the expansion-chamber, of a valve-chamber 10 between the said explosion-chamber and the nozzles, and provided with a spring-controlled valve, a bell-crank lever 5 pivotally secured to a suitable support and connected to said valve, a cam-shaft, and a centrifugal governor connected to said cam and adapted to adjust the position of the cam, substantially as described.

13. In a gas-turbine, the combination with an explosion-chamber, an expansion or compression chamber, the nozzles, a turbine, a turbine-shaft, a connection between said nozzles and the expansion or compression chamber, of a mixing-chamber, a pump adapted to deliver the explosive mixture to, and compressing the same in, said explosion-chamber, a valve-chamber 10 between the said explosion-chamber and the nozzles provided 15 with a spring-controlled valve, a bell-crank lever pivotally supported and connected to said valve, a cam-shaft, a cam movably secured on said cam-shaft, and a centrifugal governor connected to said cam and adapted 20

to adjust the position of the cam, substantially as described. 25

14. In a gas-turbine, the combination with an explosion-chamber, a turbine and connection between said explosion-chamber and the turbine, of means communicating with said 30 connection adapted to prevent the force of the explosion in said explosion-chamber from acting directly upon the turbine, substantially as described.

15. In a gas-turbine, the combination with 35 an explosion-chamber, a turbine and a connection between said turbine and the explosion-chamber, of an expansion-chamber and a valve communicating with said connection adapted to be automatically closed to prevent 40 the force of the explosion in the explosion-chamber from being directly communicated to the turbine, substantially as described.
